Primary Examiner — Brett Miller(74) *Attorney, Agent, or Firm* — ScienBiziP, P.C.**CLAIM**

The ornamental design for a storage shed as shown and described.

DESCRIPTION

FIG. 1 is a front, right and top perspective view of a storage shed, showing my new design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 1.

FIG. 12 is an enlarged view of detail 12 in FIG. 1; and,

FIG. 13 is an enlarged view of detail 13 in FIG. 2.

The dashed broken lines depict portions of the storage shed that form no part of the claimed design.

The dot-dash broken lines in FIGS. 1, 2 and 9-13 depict the boundaries of the enlarged views and form no part of the claimed design.

1 Claim, 13 Drawing Sheets(56)
